UNITED STATES PATENT OFFICE.

WILLIAM M. AUERBACHER, OF MINNEAPOLIS, MINNESOTA.

TANK-EQUIPPED DOOR FOR AUTOMOBILES.

1,177,007.

Specification of Letters Patent.

Patented Mar. 28, 1916.

Application filed June 11, 1914. Serial No. 844,418.

To all whom it may concern:

Be it known that I, WILLIAM M. AUERBACHER, a citizen of the United States, residing at Minneapolis, in the county of Hennepin and State of Minnesota, have invented certain new and useful Improvements in Tank-Equipped Doors for Automobiles; and I do hereby declare the following to be a full, clear, and exact description 10 of the invention, such as will enable others skilled in the art to which it appertains to make and use the same.

My invention relates to automobiles, and has for its object to provide a simple and 15 efficient device especially adapted for carrying water for use when needed in connection with the engine cooling system.

The invention consists in utilizing one of the doors of the automobile as a tank for 20 containing water or other liquid.

The invention is adapted to be applied to any or all of the doors of the automobile, but the chief novelty resides in utilizing the front door on the driver's side, as a tank, 25 and in making the said door vertically removable from the vehicle body so that the water may be poured therefrom into the water cooling system of the engine.

In the accompanying drawings which 30 illustrate the invention, like characters indicate like parts throughout the several views.

Referring to the drawings: Figure 1 is a fragmentary perspective with some parts 35 broken away showing the invention as applied to the front door on the driver's side, as above indicated; Fig. 2 is a detail in section on the line $x^2 x^2$ on Fig. 1; Fig. 3 is a fragmentary perspective with some parts 40 broken away, showing the invention applied to one of the hinge doors of the vehicle body; Fig. 4 is a perspective view showing a removable tank used in connection with the door shown in Fig. 3; and Fig. 5 is a detail in section taken on the line $x^5 x^5$ on 45 Fig. 4.

Referring first to the construction illustrated in Figs. 1 and 2, the numeral 1 indicates a portion of the side of the automobile body, and the numeral 2 indicates the side 50 door which is vertically removable therefrom and is provided with a reduced marginal portion 3 that fits a correspondingly formed channel 4 formed in the body wall 1. Each door is designed for use as the front 55 door on the driver's side of the automobile,

and it is preferably made in the form of a sheet metal shell, and at a convenient point at or near its top, is provided with a threaded filling sleeve 6 that is adapted to be tightly closed by a threaded stopper or plug 60 7. Preferably, the sleeve 6 is located on the inner side of the door 2 near one upper corner thereof. This tank-like door 2 is adapted to be filled with water, or other liquid, while it is in working position, or it 65 may be removed for the purpose of filling. It is adapted to be removed and inverted for the purpose of pouring the water therefrom into the cooling system of the engine; or, if used to contain gasoline, may be used 70 in a similar and obvious manner.

When applying the invention to one of the hinged doors, either front or rear, of the automobile, as illustrated in Figs. 3, 4 and 5, the said door 8 is preferably made hollow 75 and open at the top and provided with a closely fitting removable interior or lining tank 9. Such tank 9 may be conveniently provided with a top board 10 that limits the downward movement of the tank 9 into the 80 said door and gives a finished top to the door. This tank 9 also should have a filling sleeve 11 and cooperating plug 12 located near the upper portion of one end thereof.

These tank-like doors are especially 85 adapted for use in carrying water, gasoline, or lubricating oil, but may, of course, be used for carrying any other liquid. Where several of the doors of the automobile are equipped with these carrying tanks, one or 90 more thereof may be used to carry water and another to carry gasoline. The utilization of these doors as carrying tanks does not in any way detract from the appearance of the machine and takes up no space, whatever, which is useful for any other purpose. 95

What I claim is:

The combination with an automobile door in the form of a shell open at its top, of a carrying tank seated within and filling the 100 interior cavity of the said door but removable therefrom, the said tank having a top plate that normally closes the top of the opening in said door.

In testimony whereof I affix my signature 105 in presence of two witnesses.

WILLIAM M. AUERBACHER.

Witnesses:

A. E. BATCHELDER,
I. G. OVERSON.
